(57) **CLAIM**

We claim the ornamental design for a speaker for an automobile, as shown and described.

DESCRIPTION

FIG. 1 is a top perspective view of a speaker for an automobile of the present invention;

FIG. 2 is a top view thereof;

FIG. 3 is a first side view thereof;

FIG. 4 is a second side view thereof;

FIG. 5 is a third side view thereof;

FIG. 6 is a fourth side view thereof; and,

FIG. 7 is a bottom view thereof.

The broken line showing on the drawing disclosure is for illustrative purposes only and forms no part of the claimed design.
